UNITED STATES PATENT OFFICE.

FREDERIC W. ELLEBY, OF MODESTO, CALIFORNIA.

MILKER'S MASK.

1,290,140.

Specification of Letters Patent.

Patented Jan. 7, 1919.

Application filed February 19, 1917. Serial No. 149,403.

To all whom it may concern:

Be it known that I, FREDERIC W. ELLEBY, residing at Modesto, in the county of Stanislaus, State of California, have invented 5 certain new and useful Improvements in Milker's Masks; and I do declare the following to be a full, clear, and exact description of the same, reference being had to the accompanying drawings, and to the characters 10 of reference marked thereon, which form a part of this application.

This invention relates to improvements in dairy paraphernalia and particularly to a mask for use by a milker to prevent being 15 lashed in the face and eyes by the cow's tail during the milking operation.

The lashing of the face and eyes by a cow's tail, especially during fly season, is most obnoxious and many different tricks 20 are resorted to by a milker to avoid the same. None of the present day methods are satisfactory and I have therefore provided a mask to be placed over the face of the milker which shall prevent any part of the 25 tail or hairs thereof from striking the face or eyes of the milker. This leaves the animal free to lash her tail as much as desired and all evil effects are overcome.

A further object of the invention is to 30 produce a simple and inexpensive device and yet one which will be exceedingly effective for the purpose for which it is designed.

These objects I accomplish by means of 35 such structure and relative arrangement of parts as will fully appear by a perusal of the following specification and claim.

In the drawings similar characters of reference indicate corresponding parts in the several views.

40 Figure 1 is a perspective view showing the mask as it would appear in use.

Fig. 2 is a perspective view showing the mask removed from the head of the wearer.

Referring now more particularly to the 45 characters of reference on the drawings, I first provide frame supporting wires 1 shaped to substantially fit completely around the face of the wearer. These wires are suitably padded on the sides and ends by means 50 of padding 2 which may be of any desired form or material. Projecting forwardly

from wires 1 are mask supporting wires 3 fitted over which is the mask netting 4. This netting must be of such construction that it will allow the milker to see clearly through 55 same but at the same time the wires thereof must be so inter-woven as to prevent the possibility of any of the hairs of the cow's tail from being able to slap or work through the same. Such a mask for instance as an ordinary baseball mask or some such familiar mask does not answer the purpose for the reason that the wires are not shaped nor placed sufficiently close together to serve the purpose covered by my invention. A strap 60 5 is secured to the mask for the purpose of fastening same on the head of the milker and is provided with a fastening button 6 or other suitable fastening means.

From the foregoing description it will be 70 readily seen that I have produced such a device as substantially fulfills the object of the invention as set forth herein.

While this specification sets forth in detail the present and preferred construction of 75 the device, still in practice such deviations from such detail may be resorted to as do not form a departure from the spirit of the invention as defined by the appended claim.

Having thus described my invention what 80 I claim as new and useful and desire to secure by Letters Patent is:

A mask for protecting the face of a milker from being lashed by the end of a cow's tail in motion, such mask comprising a supporting frame attached to fit completely around the face of the milker and fitting closely on the skull, a pair of stiff horizontally parallel wires projecting from the supporting frame, the top one following the contour of the 90 forehead and fitting closely thereagainst, the lower one being about on a level with the chin and spaced considerably therefrom, and a nonflexible wire netting covering such framework, the mesh of such netting being 95 spaced sufficiently close to prevent any of the hairs of the animal's tail from working therethrough to strike the face of the wearer and yet of sufficient spacing to permit of easy vision therethrough.

100 In testimony whereof I affix my signature.
FREDERIC W. ELLEBY.
